(57) **CLAIM**

I claim, the ornamental design for an extremity offloading system, as shown and described.

DESCRIPTION

FIG. 1 is a perspective view of an extremity offloading system showing my design;

FIG. 2 is another perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof;

FIG. 8 is a bottom plan view thereof;

FIG. 9 is a sectional view through the line 9-9 in FIG. 3; and,

FIG. 10 is a sectional view through the line 10-10 in FIG. 7.

Evenly broken lines are used to illustrate features and/or environmental structures which form no part of the claimed design.
